UNITED STATES PATENT OFFICE.

THEODORE J. KING AND ARTHUR O. BABENDREIER, OF WASHINGTON,
DISTRICT OF COLUMBIA.

RAILWAY.

SPECIFICATION forming part of Letters Patent No. 629,568, dated July 25, 1899.

Application filed April 8, 1898. Serial No. 712,306. (No model.)

To all whom it may concern:

Be it known that we, THEODORE J. KING and ARTHUR O. BABENDREIER, citizens of the United States, residing at Washington, in the 5 District of Columbia, have invented new and useful Improvements in Railways, of which the following is a specification.

Electric and other railways which embrace an underground conduit are ordinarily provided at a suitable point with an opening communicating with the conduit-slot, the said opening being sufficiently large and being intended to permit of the passage of the plow of a car from its normal operative position to 10 a point above the surface of the railway, or vice versa. Such an opening, whether situated in the yard or at an intermediate point in the length of a railway, is a menace to the safety of pedestrians, horses, and vehicles, 15 and it is therefore highly desirable that it should be closed except when it is necessary to raise the plow of a car from or lower it to its normal operative position. Our invention 20 contemplates the provision of a simple and practical closure for an opening such as mentioned and one which is susceptible of being operated either manually or automatically when it is desired to raise or lower a plow 25 through the opening.

30 The invention will be fully understood from the following description and claims, when taken in conjunction with the annexed drawings, in which—

Figure 1 is a transverse section of an underground railway, illustrating the pit in which our improvements are arranged. Fig. 2 is a 35 plan view of the same with some parts broken away and others in section. Fig. 3 is a transverse section illustrative of the manner in which the closure is automatically operated by a car device. Fig. 4 is a detail section taken in the plane indicated by line 4 4 of Fig. 3.

Referring by letter to said drawings, A A 40 are the rails, B the conduit, and C the slot, of an underground railway, all of which may be of the ordinary or any approved construction.

D is a pit communicating with the conduit B, and E is an opening formed in the surface wall F of the pit and communicating with the 45 slot C, said opening being sufficiently large to permit of the upward or downward passage

of the plow of a car after the manner before described.

Mounted on a longitudinally-disposed shaft G in the pit D are two pairs of levers, a lever H of each pair being keyed to the shaft so as to turn therewith, while a lever H' of each pair is loose on the shaft so as to rock thereon. The said levers H H' are of the shape best shown in Fig. 1—that is to say, their upper 60 arms are curved so as to enable the plow of a car to pass between them when the closure is open, and their lower arms extend from the shaft G in directions opposite to their upper arms.

55 I are weights suitably fixed on the lower arms of the levers H H' and having for their purpose to normally hold said levers in and return them to the position shown in Fig. 1, and J J' are gates connected to the upper 70 ends of the levers. These gates J J' are of the proportional size shown in Fig. 2, and they are designed when the levers H H' are in their normal position, as shown in Fig. 1, to close the opening E, and thereby remove 75 all liability of a person or anything falling through said opening into the pit D.

70 We prefer in practice to provide means whereby the gates J J' may be opened either manually or automatically; but it is obvious 80 that when desired one of these means may be dispensed with and the other alone depended upon to open the gates. The manual means is best shown in Fig. 1 and comprises a shaft 85 K, journaled in suitable supports in the pit D, levers L, fixed on said shaft and extending above and below the same, pitmen M, connecting the upper ends of the levers L and the upper arms of the levers H, pitmen N, connecting the lower ends of the levers L and 90 the upper arms of the levers H', an arm P, fixed on the shaft K, and a handle Q, normally resting in a depression in the cover R of a manhole S and connected by a chain T with the arm P. By reason of this construction when the handle Q is drawn upwardly the levers H H' will be rocked in opposite directions and the gates J J' will be moved to opposite sides of the opening E, and said opening will be left clear for the passage of 95 the plow of a car. When the handle Q is released by the operator, the levers and the 100

gates will immediately return to their normal position and the opening E will again be closed.

The manhole S and the cover R, which latter is removable, are provided in order that a workman may readily gain access to the mechanism in the pit when it is necessary to lubricate or repair the same.

The mechanism for effecting the automatic opening of the gates J J' is best shown in Figs. 3 and 4 and comprises lugs U, arranged at the upper side of the gates J J', and a shoe V, carried by a car W. The shoe V is in the form of an open frame, with wedge-shaped or pointed ends, and is of such size as to permit the plow (not shown) to pass up and down through it. Said shoe is also of such a length and is so arranged with respect to the plow that one of its ends will have entered between the lugs U, and thereby opened the gates J J' before the plow reaches the end of the gates contiguous to the slot.

The automatic opening of the gates J J' is effected by the shoe V on a moving car entering between the lugs U. When the straight sides of the shoe reach the lugs U, the gates will have been fully opened, and the car being stopped the plow may be raised or lowered through the opening E. When the car is started and the shoe passes from between the lugs U, the gates will be immediately closed by the fall of the weights I.

In order to prevent damage to any of the parts in the event of the plow on a moving car reaching the end of the opening E contiguous to the slot C prior to the gates being opened, the inner corners of the gates at such end of the opening are beveled, as shown in Figs. 2 and 4, so as to enable the upper reduced portion of the plow to open the gates sufficiently to permit said reduced portion to pass between them until the car is stopped over the opening E.

Connected to the levers II at the inner edges thereof is a guard-plate H², and connected to the inner edges of the levers H' is a similar guard-plate H³. These plates H² H³ are provided in order to prevent the shoes on an electric plow or current-collector from catching against the gates J J' or any of the appurtenances thereof as the plow is raised.

When desirable, our improved closure may be employed in conjunction with the inclined way disclosed in our Letters Patent of April 18, 1899, No. 623,248, in which case the opening E and the closure thereof will be located at the terminal of the underground conduit, as shown in Fig. 2. When the closure is so employed, the guard-plates H² H³ enable an ascending plow to open and pass up between the gates in the event of the automatic or manual gate-opening mechanism failing from any cause to work. The opening E and its closure may, however, be arranged at any point, and when desired a plurality of openings E and closures therefor may be provided at various points.

It will be appreciated from the foregoing that our improvements are simple and practical and that they are adapted to effect a secure closure of the opening E; also, that while there is no liability of the gates being casually opened they may be very readily opened by manual labor and are also susceptible of being automatically opened in the manner described.

Having thus described our invention, what we claim is—

1. The combination with a railway having a conduit provided with a slot, and also having an opening in its surface wall communicating with the slot, said opening being sufficiently large to permit the upward or downward passage of a plow through the same; of upright levers fulcrumed at an intermediate point of their length below the surface wall of the railway and having their lower arms weighted, and gates fixedly connected to and movable with the upper arms of the levers and adapted to close the opening in the surface wall of the railway, substantially as specified.

2. The combination with a railway having a conduit provided with a slot, and also having an opening in its surface wall communicating with the slot, said opening being sufficiently large to permit the upward or downward passage of a plow through the same; of levers fulcrumed at an intermediate point of their length below the surface wall of the railway and having their lower arms weighted, gates arranged on the upper arms of the levers, and guide-plates also arranged on said upper arms of the levers, substantially as specified.

3. The combination with a railway having a conduit provided with a slot and also having a pit communicating with the conduit and provided in its surface wall with an opening communicating with the slot, said opening being sufficiently large to permit the upward or downward passage of a plow therethrough; of the two pairs of upright levers fulcrumed at an intermediate point of their length in the pit and having their lower arms weighted, gates connected to the upper arms of the levers and arranged in a plane below the surface wall of the pit, and guard-plates connecting the corresponding levers of the pairs, substantially as and for the purpose set forth.

4. The combination with a railway having a conduit provided with a slot and also having a pit communicating with the conduit and provided in its surface wall with an opening communicating with the slot, said opening being sufficiently large to permit the upward or downward passage of a plow therethrough; of upright levers fulcrumed at an intermediate point of their length in the pit and having their lower arms weighted, gates connected to the upper arms of the levers and arranged in a plane below the surface wall of the pit, a lever L fulcrumed at an intermediate point of its length, a handle connected

with said lever L, a pitman connecting one arm of the lever L and the upper arm of one gate-bearing lever, and a pitman connecting the other arm of the lever L and the upper arm of the other gate-bearing lever, substantially as specified.

5. The combination with a railway having a conduit provided with a slot and also having a pit communicating with the conduit and 10 provided in its surface wall with an opening communicating with the slot, said opening being sufficiently large to permit the upward or downward passage of a plow therethrough; of upright levers fulcrumed at an intermediate point of their length in the pit and having their lower arms weighted, gates con-

nected to the upper arms of the levers and arranged in a plane below the surface wall of the pit, and having projections at their upper sides, a car, and a shoe on the car adapted to 20 enter between the projections on the gates and thereby open said gates, substantially as specified.

In testimony whereof we have hereunto set our hands in presence of two subscribing witnesses.

THEODORE J. KING.
ARTHUR O. BABENDREIER.
